UNITED STATES PATENT OFFICE.

JOSEPH A. FIELDS, OF NEW YORK, N. Y.

DESIGN FOR A COMBINED BOTTLE AND HOLDER.

Application filed November 30, 1923. Serial No. 7,925. Term of patent 14 years.

To all whom it may concern:

Be it known that JOSEPH A. FIELDS, a citizen of the United States, and resident of the city of New York, in the county of New York and State of New York, has invented a new, original, and ornamental Design for Combined Bottle and Holder, of which the following is a specification,

reference being had to the accompanying drawing, forming part thereof, in which the figure is a perspective view of my new design of combined bottle and holder.

I claim:

The ornamental design for a combined bottle and holder as shown.

JOSEPH A. FIELDS.
